GAME OF SKILL

Raymond A. Hennings, New Orleans, La.

Application December 31, 1932, Serial No. 649,719

1 Claim. (Cl. 273—121)

This invention relates to game apparatus and it consists in the novel feature hereinafter described and claimed.

An object of the invention is to provide a game of skill consisting of apparatus in which an inclined board is used, said board is covered with felt and is provided with a series of pockets upon its upper surface. Spaced contacts are located upon the board adjacent the pockets and a series of signal lamps is mounted upon the board and the said lamps are electrically connected together and are wired to switches. A series of balls of a certain weight are adapted to close the switches whereby the electric circuit with the series of lamps is completed when a ball is located in each pocket and means are provided for projecting the balls upon the felt covered board.

A further object of the invention is to provide new and improved means for conveying the balls from the pockets and returning them to the point of projection upon the felt covered board.

In the accompanying drawings

Figure 1 is a top plan view of the game apparatus indicating the under parts thereof in dotted lines.

Figure 2 is a side elevation of the game apparatus indicating concealed parts in dotted lines.

Figure 3 is an enlarged front elevation view of the game apparatus with parts indicated in dotted lines.

Figure 4 is a diagrammatic view of wiring used in the game apparatus.

Similar numerals of reference designate corresponding parts in all the views of the drawings. The game apparatus includes a felt covered board 1 which is supported in an inclined position upon a table or floor in a usual manner. The board 1 is provided upon its upper surface with an upstanding flange 2 the area within which constitutes the playing surface of the board. The flange 2 is substantially U-shaped and its curved end is located at the upper end of the board. The ends of the flange 2 are connected with a cross piece 3 located at the lower end of the board. A partition strip 4 is mounted upon the upper surface of the board 1 and is spaced from the right hand side of the flange forming an alley 5 along which the balls are successively projected as hereinafter described. A series of partition strips 6 is mounted upon the upper surface of the board 1 and the said strips 6 are spaced from each other forming ball receiving pockets 7. Rows of pins 8 are mounted upon the board and extend substantially in alignment with the partition 6 and serve as means for directing

the balls into the pockets. Electric lamps 9 are mounted upon the upper surface of the board beyond the curved portion of the flange 2 and each lamp 9 is in alignment with one of the pockets 7 and one of the lamps 9 is in alignment with the alley 5. All of the lamps 9 are electrically connected together by wiring 10 and the lamp 9 which is in alignment with the alley is connected with an inlet wire 11. A wire 12 connects the terminal lamp with a bell signal 13 which is located under the upper portion of the board.

A spring actuated plunger rod 14 is located at the lower end of the alley 5. The plunger rod is provided with the usual leather faces and balances. When the plunger rod is withdrawn or pulled rearwardly and released the said leather face of the plunger rod drives a ball in the lower end of the alley and projects the said ball upon the play area of the board from which it may roll into one of the pockets 7. The balls are indicated at 15 and are composed of steel to give them sufficient weight and whereby they may close switches and thus complete the circuit through the lamps and bell so that the lamps will be illuminated and the bell is sounded.

One of the balls 15 is of a different color from the remaining balls, as for instance red, while the remaining balls are of steel color. The ball of distinctive color is known as the mystery ball in that if it is properly played in the game it will appear in each game and in that the value of the play made with the mystery ball is double the value of the same play made by any one of the steel colored balls. A free plunger 16 is located at the lower ends of each of the pockets 7 and is adapted to slide longitudinally as the balls enter the respective pockets. As the plunger moves under the weight of the balls it closes the circuit by bringing switch tongues 17 in engagement with each other. The tongues 17 are connected together by wire sections 18 and the terminal set of tongues is connected by means of a wire 19 with the bell 13 hereinbefore described. A wire 20 connects the other terminal set of tongues with a switch 21 and said switch 21 in turn is connected with a return wire 22. The wires 11 and 22 may be plugged in or otherwise connected in an electric circuit of approximately 110 voltage. The switch 21 may be actuated by a plunger 23 in a usual manner.

The board 1 is provided at the lower end of each pocket 7 with an opening 24 of sufficient diameter to permit the balls to pass therethrough. The opening 24 is normally closed by a plug 25. All of the plugs 25 are mounted upon

a panel 26 which is hingedly attached to the under side of the board. A plunger rod 27 is slidably mounted at the lower end of the board and one end of said plunger rod is connected 5 with the panel 26 and is adapted to swing the panel in a downward direction when the rod 27 is pushed in, thus withdrawing all of the plugs 25 from the openings 24 and permitting the balls to pass through the said openings and fall into 10 a chute 28 located under the lower end of the board 1. A cross bar 29 is carried by the plunger rod 27 and abutment studs are mounted at intervals upon the cross-bar. When the plunger rod 27 is moved inwardly the studs 30 encounter 15 the ends of the plunger 16 and move the same forwardly whereby the tongues 17 are separated from each other, the circuit is broken and the balls are forced by the end of the plunger 16 through the openings 24.

15 20 25 30 35 40 45

From the chute 28 the balls roll into a race-way 31. Said race-way is inclined downwardly under the point of projection of the balls upon the board. A hood 32 extends upwardly from the lower end of the race-way and is adapted to conduct the balls upwardly and deposit them in the lower end of the alley 5 at which point the balls are projected by using the plunger 14 as hereinbefore described.

A plunger 33 is slidably mounted in the lower 30 end of the hood 32 and the said plunger is mounted upon a lever 34 fulcrumed in a bracket 35 attached to the under side of the board. A vertically disposed plunger rod 36 is slidable through the board and its lower end is mounted 35 upon the lever 34. When the plunger rod 36 is depressed the lever 34 is swung whereby the plunger 33 is moved upwardly in the hood and the balls in the hood are elevated and the uppermost ball in the hood may roll from the upper 40 end thereof into the alley 5. A partition member 37 is carried by the lever 34 and is adapted to move across the path of the balls in the race-way 31 when the lever 34 is actuated, thereby holding back the upper balls in the race-way and permitting those in the lower part of the race-way to enter the hood. A cylinder 38 is located under the lever 34 and a piston 39 is slidable

in said cylinder. A rod 40 connects the piston with the lever 34. The parts 38, 39 and 40 serve as cushioning means for the movement of the lever 34 thus preventing parts from being injured or dislocated by rough usage. The rods 41 depend from the lower portion of the board and cross bars 42 are adjustable upon said rods. The free end of the lever 34 lies between the rods 41 and the cross-bar 42 and limits the swinging movement of the lever.

5 10 15 20 25 30 35 40 45

When the plunger 23 is moved to close the switch 21 and when each of the pockets 7 receives a ball the circuit is closed through the wiring and all of the lamps are illuminated at the same time the bell 13 is sounded. Thus a visible and audible signal is given indicating that each pocket has received at least one ball. The upper surface of the board 1 is provided with pilot pins 43 which are located at the upper ends of the rows of pins 8 and which may be struck by the balls so that the course of direction of travel of the balls is changed over the surface of the board thus making it possible to more readily supply each pocket with at least one ball. Thirteen balls are used and ten balls only are delivered into the alley. Each ball of the same weight travels on the felt and is propelled by the balanced plunger, strikes the pilot pin and is directed into one of the pockets.

I claim:—

30 35 40 45

Game apparatus comprising an inclined board having a series of pockets thereon, a circuit closing switch at the lower end of each pocket, each switch having a slideable plunger extending into one of the pockets, electric conductors connecting the switches in the form of a group and in series, a source of electric supply connected with one of the terminal switches of the series, an electric signal connected with the other terminal switch of the series, a series of balls adapted to roll over the board and enter the pockets and slide one of the plungers and close the switch, the number of balls being equal to or greater than the number of switches and manually operable means for projecting the balls upon the board.

RAYMOND A. HENNINGS.
